DESIGN FOR A CANDLEHOLDER

Joseph Cucchiara and Bennett Raphaelson,
Brooklyn, N. Y.

Application December 10, 1948, Serial No. 150,076

Term of patent 14 years

(Cl. D48—2)

To all whom it may concern:

Be it known that we, Joseph Cucchiara and Bennett Raphaelson, both citizens of the United States, both residing at Brooklyn, New York, in the county of Kings and State of New York, have invented a new, original, and ornamental Design for a Candle Holder, of which the following is a specification, reference being had to the accompanying drawing, forming a part thereof.

In the drawing:

Fig. 1 is a front elevational view of a candle holder, showing my new design;

Fig. 2 is a side elevational view; and
Fig. 3 is a top plan view of the same.

I claim:

The ornamental design for a candle holder, as shown.

JOSEPH CUCCHIARA.
BENNETT RAPHAELSON.
